UNITED STATES PATENT OFFICE.

THEODORE HAVILAND, OF AMBAZAC, FRANCE.

DESIGN FOR A COVERED DISH.

SPECIFICATION forming part of Design No. 25,024, dated December 31, 1895.

Application filed September 26, 1895. Serial No. 563,806. Term of patent 7 years.

To all whom it may concern:

Be it known that I, THEODORE HAVILAND, a citizen of the United States, residing at Ambazac, in the Department of Haute-Vienne, Republic of France, have invented and produced a new and original Design for Dishes; and I do hereby declare the following to be a full, clear, and exact description of the same, reference being had to the accompanying drawings, forming a part thereof.

The principal feature of my design consists in a covered dish marked off into sections, having the base of the dish and periphery of the cover ornamented with a chain-like decoration and simulated vine-leaves.

Figure 1 represents a side view of the dish; Fig. 2, a face view of the cover.

In Fig. 1, A A represent the chain-like and simulated vine-leaf decoration at the base of the dish and periphery of the cover; B B, the sections into which the cover and upper por-

tion of the dish are divided; and C C C, the ornamentations of the handles. The chain-like decorations A A at the base of the dish and periphery of the cover are indented at regular intervals corresponding with the sections B B. ²⁵

In Fig. 2 the indentations of the periphery of the cover are marked with ornamentations representing leaves and fruit.

The decorations of the handles, Figs. 1 and ³⁰ 2, represent grape-vines with leaves and fruit at the points where the handles join the body of the dish.

What I claim is—

The design for a dish substantially as shown ³⁵ and described.

In testimony whereof I have affixed my signature in presence of two witnesses.

THEODORE HAVILAND.
